UNITED STATES PATENT OFFICE.

ALEXANDER H. TRUMBULL, OF STRATFORD, CONNECTICUT.

HOLDER FOR COLLAPSIBLE TUBES.

Application filed December 20, 1920. Serial No. 431,941.

To all whom it may concern:

Be it known that I, ALEXANDER H. TRUMBULL, a citizen of the United States, residing at Stratford, county of Fairfield, State 5 of Connecticut, have invented an Improvement in Holders for Collapsible Tubes, of which the following is a specification.

This invention relates to a holder for collapsible tubes and is especially adapted to 10 receive and permanently retain a tube of tooth paste or the like, it being the prime object to remove the ordinary screw cap from the tube and to securely hold the tube in the novel collapsible tube holder by means of the 5 screw threads on the neck of the tube.

Another object of this invention is to provide a novel collapsible tube holder having a backing plate adapted to lie next to the body of the tube, forming a substantially rigid plate 0 against which the tube may be pressed to exhaust the contents from the tube. With my novel holder the entire contents of the tube may be completely expelled with very little trouble and without the need of folding 5 over the empty sections of the tube, as is customary in the use of a tube of tooth paste.

A further object being to provide a collapsible tube holder with an internal screw threaded portion for receiving the neck of 3 the tube, and with a simple, easily operated shut-off connection to be opened and closed before and after squeezing some of the contents from the tube. I provide a sanitary tube holder having comparatively few parts which may be readily disassembled and cleansed, when affixing a new tube in place.

A still further object of the invention is to provide a novel collapsible tube holder with an outlet adapted to convert any shape discharge of substance from the tube into a flat ribbon; it being best adapted to convert tooth paste into a ribbon, which is more easily applied to a tooth brush.

The above and other objects of my invention will more fully appear from the following description and drawing, and will be especially pointed out in the annexed claims.

Fig. 1 is a view in elevation of my novel collapsible tube holder having a tube in place, and showing one mode in which the holder may be hung up;

Fig. 1^a, a similar view, partially in section, it being broken away to show the manner in which the contents of the tube is expelled;

Fig. 2, a fragmentary sectional view on an enlarged scale of the lower outlet portion;

Fig. 3, an enlarged view in front elevation of the portion seen in Fig. 2;

Fig. 4, a cross sectional view taken on line 4—4, Fig. 1;

Fig. 5, shows a modified form of my novel collapsible tube holder; and

Fig. 6 is a sectional view thereof, taken through the holder the tube being in elevation.

In Figs. 1—4, 10 denotes the body portion of my novel collapsible tube holder, which forms a backing plate for the collapsible tube 11. The body 10 may be of any desired configuration or design, but is preferably 70 semi-circular at the portion intended to lie adjacent the tube, the upper portion 12 being of reduced size to provide a handle, in which may be provided an aperture 13 to aid in hanging up the holder. The lower 75 part of the holder, integral with the body portion, is formed into an annular cup shaped bottom 14, the inside surface 15 of which is tapered to conform with the bevel found on the top of the ordinary collapsible tube. As seen in Fig. 2, the head 16 of the tube 80

rests on the taper in the bottom of the holder, which aids in expelling the last of the contents in the tube when it is pressed against the bottom of the holder. In this embodiment the bottom 14 is provided with a central aperture 17 adapted to receive the screw threaded neck 18 of the tube, which projects outside the bottom and receives a retaining cap number 19. The internal screw threads 90

20 of the cap member communicate with a passage 21, through which the paste, or other contents of the tube is forced to the outside. The passage makes its outlet to one side of the center of the bottom of the cap, which bottom is arc-shaped and has a shut-off member 22 reciprocating thereon. The shut-off member may be held for reciprocation in any desired manner, and is shown herein being supplied with a spring wire 23 which passes 100

through the member 22 and finds a pivot on each side of the cap. In the lower surface of the arc-shaped bottom is a groove 24, receiving a projection 25 on the shut-off member, which guides and limits the movement 105 of the shut-off member over the arc-shaped surface of the cap.

The passage 21 in the cap is a narrow oblong one, this invention not being intended to be limited to that specific form, which is 110 adapted to convert the substance squeezed therethrough into a flat ribbon shaped strip,

2
the particular advantage being to convert the round discharge of ordinary tubes of tooth paste into a ribbon, which is especially applicable to a tooth brush.

- 5 In using my novel collapsible tube holder it may be easily held and operated by one hand, or may be operated while in a position, like shown in Figs. 1 and 1^a, attached vertically on the side of a wall or cabinet, or 10 it may be used while in a horizontal position on a table. I have provided a pair of lugs 26, formed on the outside of the body portion 10, which act as legs for supporting my novel holder and to prevent it from rolling.
- 15 The modification of this invention, illustrated in Figs. 5 and 6 of the drawing, comprises a handle 27 having a laterally offset cup shaped portion 28, annular in shape and adapted to receive the top portion of a 20 collapsible tube, the bottom of said cup portion being tapered, similar to the taper 15 of the holder described above. The screw threaded neck 18 of the tube is received in a centrally located aperture in the bottom 25 of the portion 28 and is retained in place in the cup by a cap 29. Like the cap 19, the cap 29 has a passage 30 connecting the internally screw-threaded aperture with the outside surface, preferably the bottom, the 30 lower portion of the cap being of reduced diameter and having an annular groove 31. 32 denotes a revoluble cap thereon. The revoluble cap is provided with an eccentrically arranged opening 34 designed to register with the passage 30 when in one position, 35 and to be moved away from the passage by a simple rotation of the revoluble cap.

In operation this novel collapsible tube holder is simple, rapid and easy to attach to an ordinary collapsible tube. The screw threaded cap of the tube is first removed and the tube is placed in position in the holder, the neck 18 projecting through the aperture in the bottom thereof. My improved cap 19 is then screwed on the neck of the tube, which serves to securely fix the tube in place in the holder, and the device is then ready for use.

The advantages of this invention will obviously become apparent from an understanding of the foregoing detailed description. My novel collapsible tube holder eliminates the necessity of removing and replacing the ordinary cap each time an amount of the contents of the tube is needed, which operation requires the use of two hands. With my improved holder it is easily possible to exhaust the entire contents of the tube and to conveniently operate it with only one hand.

It is to be understood that the construction disclosed herein is illustrative but not restrictive and that the same may be modified within the meaning and scope of the following claims.

65

1. In combination a pliable container having extrudable substance therein, a threaded neck with an opening through which the substance passes, a curved holder open at one side, said holder forming a backing for the container and adapted for attachment to a support; a cupped end portion on said backing adapted to receive the end of the pliable container, an opening therein through which the threaded neck passes, and a threaded cap to attach said container to the holder, said cap having an opening therein which will shape said substance into substantially ribbon shape portions when pressure is exerted on the pliable container to extrude said substance from the container, and means associated with said cap to open and close said opening.

100

2. A device of the class described comprising a curved holder open at one side thereof and provided at one end with a cup-shaped portion adapted to substantially fit the end of a collapsible tube, said holder adapted for attachment to a support and provided with means to prevent its rolling on the support, said cup-shaped portion being provided with an opening therein, a collapsible tube having its body portion resting in the curved portion of the holder with its end seated in said cup-shaped portion and also having a threaded neck extending through said opening, and a perforated threaded retaining cap member threaded on said neck and clamping the end of the tube to the holder.

105

3. A device of the class described comprising a curved holder open at one side thereof and provided at one end with a cup-shaped portion adapted to substantially fit the end of a collapsible tube, said holder adapted for attachment to a support and provided with means to prevent its rolling on the support, said cup-shaped portion being provided with an opening therein, a collapsible tube having its body portion resting in the curved portion of the holder with its end seated in said cup-shaped portion and also having a threaded neck extending through said opening, a perforated threaded retaining cap member threaded on said neck and clamping the end of the tube to the holder, and a movable closure for the opening in the cap member.

110

In testimony whereof I affix my signature.
ALEXANDER H. TRUMBULL.
